UNITED STATES PATENT OFFICE

MICHAEL STACHO, OF CLEVELAND, OHIO

TELEVISION SCANNING DEVICE

Application filed May 1, 1930. Serial No. 448,965.

This invention relates to new and useful improvements in the art of television and more particularly to a scanning device for use in television apparatus.

The primary object of the invention is to provide, in a manner as hereinafter set forth, a television scanning device embodying a pair of opposed, co-acting rotary disks which are provided with a novel arrangement of intersecting slots.

Another important object of the invention is to provide a television scanning device of the character described embodying a pair of rotatably mounted disks having co-acting intersecting slots therein for the passage of the light pencils or beams, one of said disks further having operatively associated therewith electromagnetic means for retarding or dragging the same at the completion of each revolution in a manner to cause the same to rotate periodically at a reduced speed as compared with the other disk.

Other objects of the invention are to provide a television scanning device of the character set forth which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and therein:—

Figure 1 is a vertical longitudinal sectional view of a television scanning device constructed in accordance with this invention.

Figure 2 is a sectional view taken substantially on the line 2—2 of Figure 1 looking in the direction indicated by the arrows.

Figure 3 is a detail view in elevation showing the scanning disk with which the electromagnetic means is operatively associated.

Figure 4 is a detail view in elevation showing the scanning disk which is associated with the disk illustrated in Figure 3.

Referring to the drawings in detail, it will be seen that the reference numeral 1 designates a base upon which is mounted a stand-

ard 2 which supports an electric motor 3 which is energized through the conductor wires 4 and 5. A rheostat 6 is interposed in the conductor wire 4 for controlling the speed of the motor 3.

The armature shaft 7 of the motor 3 projects forwardly therefrom and is provided with an obtuse free end portion 8 which terminates in a flat foot 9 to which is secured by any suitable means a disk 10 having a radially disposed slot 11 extending from its center to a point adjacent the marginal edge of said disk. The disk 10 is disposed coaxially with respect to the main portion of the armature shaft 7. The marginal portion of the disk 10 is formed to provide a forwardly and inwardly curved flange 12.

A disk 13 is disposed in frictional engagement with the forward base of the disk 10 and is provided with a curved marginal flange 14 disposed within the flange 12 of the disk 10. The disk 13 is provided with a spiral slot 15 extending from a central portion thereof to a point adjacent the periphery of said disk, as clearly illustrated in Figure 3 of the drawings.

A reflector 16 is fixed on the armature shaft 7 in spaced relation to the disk 10 by any suitable means, said armature shaft being shown provided with a flange 17 against which the reflector 16 is disposed. A neon light tube 18 is disposed between the disk 10 and the reflector 16. A lens 19 is mounted forwardly of the disk 13 in an opening provided therefor in the supporting structure 20 which is mounted on the base 1.

Disposed adjacent the forward side of the disk 13 at the marginal portion thereof is an electro-magnet 21 which is energized from any suitable source through the medium of the conductor wires 22. Mounted on the forward side of the disk 13 at a point adjacent the outer end of the slot 15 is a disk of magnetic metal 23 which passes the magnet 21 in close relation thereto upon rotation of said disk 13. Also, mounted in spaced relation on the forward side of the disk 13 is a plurality of counterweights 24 of non-magnetic material which are for the purpose of counterbalancing the member 23.

In operation, the motor 3 is energized to rotate the shaft 7 and the disk 10 and the disk 13 which is mounted on said disk 10. When the magnetic lug or disk 23 on the disk 13 passes the electromagnet 21, the same is attracted thereto and the rotary movement of said disk 13 is retarded as compared with the speed of the disk 10.

It is understood, of course, that the disk 13 is rotated by the disk 10 by reason of the fact that the same is supported thereon and frictionally engaged therewith and the magnet 21 is of sufficient strength to overcome the frictional connection between the disk 13 and the disk 10. The retarding or dragging of the disk 13 occurs once in every complete revolution of said disk. When the speed of the disk 13 falls below that of the disk 10, the point at which the spiral slot 15 intersects the radial slot 11 moves progressively outward by reason of the difference in the speed at which the two disks are rotated, as will be readily understood. The pencil or beam of light is projected from the disks through the lens 19 and on to the subject (not shown).

It is believed that the many advantages of a television scanning device constructed in accordance with this invention will be readily understood, and although the preferred embodiment of the invention is as illustrated and described, it is to be understood that changes in the details of construction may be had which will fall within the scope of the invention as claimed.

35 What is claimed is:—

1. A television scanning device of the character described comprising a pair of rotatable disks having slots therein for the passage of light to a subject, and magnetic means for periodically retarding the rotation of one of said disks with respect to the other of said disks with each revolution thereof.

40 2. A television scanning device of the character described comprising a disk mounted for rotation, another disk mounted on the first named disk for rotation therewith and means for periodically retarding the speed of rotation of the second named disk with respect to the first named disk, said disks being provided with slots for the passage of light to a subject.

45 3. A television scanning device of the character described comprising a rotary disk, said disk being provided with a radial slot, another disk mounted on the first named disk for frictional rotation therewith and having a spiral slot intersecting the slot of the first named disk and means for retarding the speed of rotation of the second named disk with respect to the first named disk at the end of each revolution thereof.

50 4. A television scanning device of the character described comprising a rotary disk having a radial slot therein, another disk mount-

ed on the first named disk and frictionally engaged therewith for rotation thereby, said second named disk being provided with a spiral slot intersecting the slot of the first named disk and means for periodically decreasing the speed of rotation of the second named disk below the speed of rotation of the first named disk.

55 5. A television scanning device of the character described comprising a rotatable disk having a radial slot therein, a flange on the marginal portion of the disk, another disk mounted on the first named disk and frictionally engaged therewith for rotation thereby and having a spiral slot therein intersecting the slot in the first named disk, a flange on the marginal portion of the second named disk disposed in the flange of the first named disk, and means for decreasing the speed of rotation of the second named disk at the end of each revolution of the same relative to the speed of rotation of the first named disk.

60 In testimony whereof I affix my signature.
MICHAEL STACHO.
